UNITED STATES PATENT OFFICE.

FRANK E. SMALL, OF JAMAICA, NEW YORK.

MAGAZINE-CRAYON.

1,393,251.

Specification of Letters Patent. Patented Oct. 11, 1921.

Application filed March 25, 1920. Serial No. 368,480.

To all whom it may concern:

Be it known that I, FRANK E. SMALL, a citizen of the United States, and resident of Jamaica, in the county of Queens and State 5 of New York, have invented new and useful Improvements in Magazine-Crayons, of which the following is a specification.

This invention relates to a new and improved crayon holder of the type adapted 10 to contain a plurality of crayons which may be used selectively.

A device of this character is useful in any work which necessitates the coloring, marking or checking of articles in various 15 colors, either for artistic purposes or for purposes of identification or classification. The crayons being in a single holder are not in any danger of being mislaid and are also protected against being broken or otherwise 20 damaged. The device is adapted to be readily and quickly adjusted to change from the use of one crayon to another and therefore saves the time of the user in changing from one color to another. The magazine of the 25 holder acts as a container for the several crayons and is compact in form, so that my invention combines in one device the functions of container and holder grip for use.

It is an object of my invention to provide 30 a new and improved crayon holder which is particularly adapted for quick adjustment and use and which is simple in construction and positive in operation. It is also an object to provide a holder which is compact 35 and convenient in form, and relatively inexpensive to manufacture. It is a further object to provide a holder in which the crayons are fully protected against breaking or other injury and in which means is provided for ready identification of the desired 40 crayon. Other and further objects will appear as the description proceeds.

My improved crayon holder comprises a magazine containing the crayons in circular 45 formation and an adjustable holder pivoted relative to the magazine so that it may be rotated to register with the housing of any desired crayon. In the more specific embodiment which I have disclosed herein by 50 way of example I have formed the magazine of a plurality of tubes held in circular formation by ferrules which expose a portion of the tubes. These tubes may be colored to correspond to the crayons they 55 contain and thus serve as a ready means of identification readable even by an illiterate

user or in poor light. I have also provided means adapted to maintain the holder in alinement with any desired crayon tube and yet adapted to permit ready change from 60 one tube to another without any adjustment other than the mere moving of the holder. I have further provided means whereby the holder may be maintained in a neutral position out of alinement with any tube. Provision 65 of this neutral position is of value in preventing breaking the crayons as otherwise when the holder is out of use there is a tendency for a crayon to drop down so as to be partly within the holder grip and this 70 crayon may be broken when the holder is turned on being put into use again.

I have illustrated a preferred embodiment 75 of my invention in the accompanying drawings, in which—

Figure 1 is a side view of my improved crayon holder;

Fig. 2 is a view of Fig. 1 as seen from below;

Fig. 3 is a view of Fig. 1 as seen from the 80 left;

Fig. 4 is a section on the line 4—4 of Fig. 3; and

Fig. 5 is a section on line 5—5 of Fig. 2 with the grip in neutral position. 85

The crayon holder consists of a magazine member and a holder member, the magazine comprising a plurality of tubes 6 held in circular relation by the ferrule 7 at the lower end and the ferrule 8 at the upper end, the 90 upper ends of the tubes being closed by the plate 9 and the upper end of the ferrule 8 closed by the cap 10, the outer portion of which is preferably square in contour so as to prevent the holder from rolling when 95 placed on a plane surface.

The holder member has a circular base portion 12 adapted to cover the lower ends of the tubes 6 and an extended grip portion 13 having an opening 14 therethrough adapted to be placed in alinement with the opening in a crayon tube. The lower part of the member 13 is split and is externally screw threaded and carries the collar member 15 which by being screwed downward closes 105 the splits and thus contracts the member 13 so that it grips the crayon 16 therein. Fas- 100 tened to the center of the inner face of the member 12 is the rod 17 which extends longi- tudinally through the central space between 110 the crayon tubes and through the plate 9. This rod has a nut 18 screwed to its inner end

and is surrounded by a spring 19 bearing against the plate 9 and the nut 18. The lower edge of the ferrule 7 has a series of equally spaced indentations 20 therein, corresponding in number to the number of crayon tubes, and the adjacent edge of the member 12 carries a single lug 21 adapted to interfit with any desired one of the indentations, its relation to the opening 14 being such that when interfitted in an indentation the opening 14 is in alinement with a crayon tube.

The spring 19 by its bearing on the plate 9 and nut 18 exerts an inward tension on the rod 17, thereby holding the member 12 yieldably in intimate contact with the lower end of the tubes 6 and ferrule 7. The rounded contour of the indentation 20 and lug 21 is such that while the spring serves to hold them as they are placed, it is nevertheless easy to rotate the member 12 and thus move the lug to another indentation.

At one point, I have shown an indentation 22 similar to those designated 20 but located midway between two of the latter. When the lug 21 is in this indentation 22 the opening 14 is located, as shown in Fig. 5, in a neutral position and no crayon can drop down into the opening.

If there were no neutral position it would be possible to prevent crayons from dropping entirely out of the holder by screwing down the clamp collar 15, but in this case a crayon could drop down until it was partly within the opening 14 and there would be danger of breaking the crayon by attempting to turn the member 12. With the member 12 in neutral position it is impossible for any crayon to drop into the holder opening.

My improved crayon holder may be quickly manipulated to change from one crayon to another without operation of any separate locking device and with but a single rotary motion of the holder grip member. The crayon is fully protected at all times against breaking. The several crayon tubes may be readily loaded by placing the grip opening 14 in alinement with each tube in turn and dropping the crayon through the opening 14 into its proper tube, the grip collar being screwed out of clamping position to fully open the grip.

I claim:

1. A crayon holder comprising a magazine member constructed and arranged normally to contain a plurality of crayons, a holder grip member and a pivot therefor extending into the magazine member, spring means associated with the pivot member and the magazine and adapted to maintain the grip member in intimate engagement with the magazine member, and interlocking means upon the grip and magazine adapted to maintain them yieldably in predeter-

mined relation but to permit relative rotation thereof upon application of sufficient rotative force and to permit rotation of the one relative to the other.

2. A crayon holder comprising a magazine member adapted to contain a plurality of crayons, a holder grip member and a pivot therefor extending into the magazine member, locking means between the grip and magazine comprising a lug on one of said members, and coacting indentations on the other of said members, and spring means associated with the pivot and the magazine constructed and arranged normally to maintain the magazine and grip in intimate contact for rotation of one relative to the other and to maintain the lug yieldingly in any predetermined indentation but to permit relative rotation thereof upon application of sufficient rotative force.

3. A crayon holder comprising a magazine member adapted to contain a plurality of crayons, a holder grip member and a pivot therefor extending into the magazine member, locking means between the grip and magazine comprising a lug on one of said members and coacting indentations on the other of said members, and spring means associated with the pivot and the magazine constructed and arranged normally to maintain the magazine and grip in intimate contact for rotation of one relative to the other and to maintain the lug in any predetermined indentation, the lug and indentations being of such contour as to permit the holder grip member to be rotated against the resistance of the spring means to disengage the lug from an indentation.

4. A crayon holder comprising a magazine member having openings therein adapted to contain crayons, a holder grip member provided with an outwardly extending pivot rod for the magazine and having an opening by rotation of the grip member therethrough adapted to be placed in alinement with any one of said crayon openings, interlocking means on said grip and magazine members constructed and arranged normally to maintain the opening in the grip in alinement with any predetermined crayon opening or out of engagement with any such opening, said interlocking means being arranged for relative disengagement upon the application of sufficient rotative force.

5. A crayon holder comprising a magazine consisting of a plurality of tubes, ferrules retaining the tubes in circular formation, a holder grip member associated with the lower end of the magazine having an opening therethrough adapted to be placed in alinement with the opening of any of said tubes, a pivot rod fixed to said holder grip member extending centrally of said tube formation, a spring associated with the upper end of the pivot rod and of the maga-

- zine member and constructed and arranged normally to maintain the holder grip member in intimate rotatable engagement with the lower end of the magazine member, a plurality of spaced indentations on the lower edge of the magazine, and a lug on the upper edge of the holder grip member adapted to interfit with any one of the indentations and when so interfitted normally to maintain the opening in the holder grip in alinement with one of said tubes until intentionally moved by the application of sufficient rotative force.
6. A crayon holder comprising a magazine consisting of a plurality of tubes, ferrules retaining the tubes in circular formation a holder grip member associated with the lower end of the magazine having an opening therethrough adapted to be placed in alinement with the opening of any of said tubes, a pivot rod fixed to said holder grip member extending centrally of said tube formation, a spring associated with the upper end of the pivot rod and of the magazine member and adapted normally to maintain the holder grip member in intimate rotatable engagement with the lower end of the magazine member, a plurality of spaced indentations on the lower edge of the magazine, a lug on the upper edge of the holder grip member adapted to interfit with any one of the indentations and when so interfitted to normally maintain the opening in the holder grip in alinement with one of said tubes, but to permit relative rotation of the parts upon application of sufficient rotative force, a supplemental indentation on said magazine spaced between a pair of said before-mentioned indentations adapted to receive said lug and when interfitted with said lug to maintain the opening in the holder grip member out of alinement with any of the tubes.
7. A crayon holder comprising a magazine consisting of a plurality of tubes, ferrules retaining the tubes in circular formation and a plate at the upper end of said tubes having a central opening therein, a holder grip member associated with the lower end of the magazine having an opening therethrough adapted to be placed in alinement with the opening of any of said tubes, a pivot rod fixed to said holder grip member extending centrally of said tube formation and through the central opening in said plate, a nut on the upper end of said rod and a spring surrounding said rod and interposed between the plate and nut, the spring being adapted normally to maintain the holder grip member in intimate engagement with the lower end of the magazine member, a plurality of spaced indentations on the lower edge of the magazine, a lug on the upper edge of the holder grip member adapted to interfit with any one of the indentations and when so interfitted to maintain the opening in the holder grip in alinement with one of said tubes, a supplemental indentation on said magazine spaced between a pair of said before-mentioned indentations adapted to receive said lug and when interfitted with said lug to maintain the opening in the holder grip member out of alinement with any of the tubes, the interfitting lug and indentations being of such contour as to permit the holder grip member to be rotated against the resistance of the aforesaid spring to disengage the lug and an indentation.
8. A crayon holder comprising a magazine consisting of a plurality of tubes, ferrules retaining the tubes in circular formation and a plate at the upper end of said tubes having a central opening therein, a holder grip member associated with the lower end of the magazine having an opening therethrough adapted to be placed in alinement with the opening of any of said tubes, a pivot rod fixed to said holder grip member extending centrally of said tube formation and through the central opening in said plate, a nut on the upper end of said rod and a spring surrounding said rod and interposed between the plate and nut, the spring being adapted normally to maintain the holder grip member in intimate engagement with the lower end of the magazine member, a plurality of spaced indentations on the lower edge of the magazine, a lug on the upper edge of the holder grip member adapted to interfit with any one of the indentations and when so interfitted to maintain the opening in the holder grip in alinement with one of said tubes, a supplemental indentation on said magazine spaced between a pair of said before-mentioned indentations adapted to receive said lug and when interfitted with said lug to maintain the opening in the holder grip member out of alinement with any of the tubes, the interfitting lug and indentations being of such contour as to permit the holder grip member to be rotated against the resistance of the aforesaid spring to disengage the lug and an indentation.
9. A crayon holder comprising a base member of substantially circular form, a grip member extending from one side thereof, a lug projecting from the opposite side of said base member adjacent its edge, a magazine device comprising a sleeve having an indentation in its edge, means for positioning said magazine device in substantial axial alinement with said base member, and means for resiliently retaining said indentation in engagement with said lug.
10. A crayon holder comprising a base member having a grip member extending therefrom, a magazine having a plurality of compartments, a sleeve member secured to said magazine and having a plurality of indentations in its edge, one at least of such indentations being at a point intermediate adjacent compartments of the magazine, a

lug projecting from said base member for rod, resilient means interposed between an 10
selective engagement with said indentations, element of said rod and an element of the
means for securing said magazine relatively magazine whereby to press the latter into
to said base member, and means for resili- engagement with the base member, and a
5 ently retaining said lug in engagement with cap member for such magazine having a
a selected one of said notches. plurality of angularly disposed faces. 15

11. A crayon holder comprising a base member, a rod rigidly projecting therefrom, a magazine turnable about the axis of said

Signed by me at Jamaica, N. Y., this 22nd day of March, 1920.
